UNITED STATES PATENT OFFICE.

GEORGE HAZELTON, OF WHITEHALL, LONDON, ENGLAND, ASSIGNOR TO VICKERS
LIMITED, OF WESTMINSTER, LONDON, ENGLAND.

MACHINE GUN.

Application filed March 19, 1919. Serial No. 283,610.

(GRANTED UNDER THE PROVISIONS OF THE ACT OF MARCH 3, 1921, 41 STAT. L., 1313.)

To all whom it may concern:

Be it known that I, GEORGE HAZELTON, a subject of the King of Great Britain, residing at the Admiralty, Whitehall, in the 5 county of London, England, have invented certain new and useful Improvements in and Relating to Machine Guns, of which the following is a specification.

This invention relates to machine guns of 10 the kind in which the barrel recoils and the lock reciprocates as in the well known Vickers automatic gun for example and has for its chief object to enable a more rapid rate of fire to be obtained than has hitherto 15 been practicable in guns of this kind.

According to this invention there is provided at the muzzle end of the gun a piston-like member formed on or secured to the gun barrel and contained in a fixed cylinder 20 or cup having an opening in line with the bore of the gun barrel for the bullet to pass through and also having one or more lateral apertures or ports disposed behind the position occupied by the piston-like member 25 when the gun barrel is stationary and the gun ready for firing, so that the piston-like member must move rearwardly with the gun barrel a certain distance before the apertures or ports are uncovered to allow 30 the escape of the propellant gases, and there is also provided in addition to the usual main or fusee spring of the gun an auxiliary spring which is mounted on or otherwise arranged to act upon the barrel or piston-like 35 member and which acts as a buffer for the barrel on the recoil stroke and then after the barrel is brought to rest, acts as a quick return spring.

In the preferred form the inner face of 40 the cylinder is shaped to trap to some extent the propellant gases so as to cause a rapid building up of back pressure on the piston-like member. This may be conveniently effected by forming the inner face with one 45 or more recesses or pockets or similar parts.

Where required, the main or fusee spring of the gun can be arranged to have its leverage slightly increased at or near the termination of the rearward movement of the 50 lock so as to retard suddenly this movement of the lock and to increase the speed at which the lock returns towards its firing position. This may be conveniently arranged

by making the rear one of the usual two links connecting the spring to the fusee to 55 take a higher or lower path than is usual such as by forming the fusee with an enlargement or by securing a cam shaped or like part thereon.

The accompanying drawings illustrate a 60 gun of the kind referred to embodying this invention. Figs. 1 and 1^a are longitudinal sections shewing as viewed from the right a Vickers automatic gun provided with the 65 improvements,

Figure 2 is an enlarged section of the muzzle end of the gun as viewed from the left,

Figure 3 is an enlarged view of the fusee and its parts as viewed from the left with the usual cover plate for the main or fusee 70 spring removed. Figures 4 and 5 are elevations at right angles to each other of a cushioning and return spring of a different form from that shown in Figures 1 and 2 and advantageously employed when the gun is 75 mounted on aircraft or in other places where feeding in of a fresh cartridge belt requires special consideration as will be hereinafter explained.

The gun barrel 1 is provided at its muzzle 80 end with a cap or piston 2 working within a cylinder or cup 3 having its outer end 4 formed with an aperture 5 in line with the bore of the barrel so that the bullet can travel through the bore, the piston 2 and the 85 cylinder 3, without hindrance. The said piston 2 may be connected to the barrel in the same way as the corresponding part of the existing muzzle attachment of the Vickers 90 automatic gun and may be of similar formation. The inner face of the outer end 4 of

the said cylinder or cup is shown as formed with an annular recess or pocket 6 with the inner edge sloped as shown to cause the propellant gases travelling behind the bullet 95 and entering said cylinder or cup to be readily deflected laterally with respect to the barrel and to some extent trapped between the outer end of the cylinder 3 and the piston 2 to cause a rapid building up of back 100 pressure on the latter. In the wall of the cylinder 3 and in a position behind that occupied by the piston 2, when the gun is ready for firing, a number of holes or ports 7 are formed which become uncovered by the 105 travel of the piston 2 to the rear, so that on

the recoil of the said piston and the gun barrel, these ports will become uncovered after a certain part of the stroke has taken place to allow the propellant gases in front of the piston to escape.

An auxiliary spring 8 is shown freely mounted on the barrel adjacent to the piston 2 which can travel rearward a predetermined distance before compressing the spring against a fixed part 14 of the gun. This spring cushions the recoil movement after a certain interval of time has elapsed and also assists in the return of the barrel and the piston 2 to the correct working position for firing. The auxiliary spring may be placed in any other suitable position than that shown to effect the same actions on the barrel.

When a machine gun arranged as above described is mounted on aircraft it may be necessary to provide a device other than the usual crank handle for manually causing rearward movement of the barrel and the lock when a fresh cartridge belt has to be fed in. A device for this purpose is already known in aerial gunnery and consists of a hand lever working in conjunction with the usual crank handle so as to simulate the movements of the barrel and the lock that occur when the gun is actually firing. With a spring of helical form as shown in Figure 1, the necessary movements may not be possible owing to the fact that the length of the spring when fully compressed prevents the necessary degree of retraction of the barrel from taking place to allow a fresh belt to be fed in. This difficulty may be overcome by employing (instead of the helical spring 8) a conical spring 9 as shown in Figures 4 and 5 which when subjected to compression under the action of the hand lever and crank handle above referred to, occupies only a small length on the gun barrel, so that the necessary rearward movement of the barrel can be obtained for feeding in a fresh cartridge belt.

By suitably designing the parts at the muzzle end of the gun and the cushioning spring, a considerable variation in the speeding up of the rate of fire of the gun can be effected without its being necessary to vary the tension of the main or fusee spring of the gun. In cases, however, where it may be desired to cause the leverage of the main or fusee spring of the gun to be increased at or near the termination of the rearward movement of the lock of the gun to cause a quicker retardation of this movement and a quicker return of the lock to the normal firing position, this can be effected by providing the usual fusee 10 with a block 11 of cam or other suitable shape, so that the rear link 12 of the usual two links connecting the fusee 10 to the spring 13, is caused at the termination of its movement to take a

higher or lower path as the case may be, than is usual in the normal construction for this part of the gun. The aforesaid block is but seldom required to be embodied in the gun, as the desired increase in the rate of fire 70 can be obtained by suitable modification of the design of the device at the muzzle end.

What I claim and desire to secure by Letters Patent of the United States is:—

1. In machine guns of the kind referred 75 to, the combination of a piston-like member on the gun barrel adjacent to the muzzle end, a muzzle cup which is provided with one or more ports arranged behind the stationary position of the piston-like member when the gun is ready for firing, and within which the muzzle of the gun barrel is situated, the said port or ports being passed by the said member, when the gun is fired, to allow the gases in the cup to escape, and a spring additional to the main spring of the gun, arranged to act upon the barrel to constitute a buffer on the recoil stroke and a quick return means after the recoil movement of the barrel has been arrested, substantially as and 90 for the purpose described.

2. In a machine gun of the barrel recoiling type, the combination with the reciprocating lock, the main fusee spring and the fusee upon which said spring operates, of means 95 for increasing the leverage of the said spring at or near the termination of the rearward movement of the lock.

3. In a machine gun of the barrel recoiling type, the combination with the reciprocating lock, the main fusee spring and the fusee upon which said spring operates, of links interposed between said spring and said fusee, and a block on said fusee, which block at or near the termination of the rearward movement of the lock comes against the rear one of said links to cause it to take a path further away from the axis of movement of the fusee than is customary. 100

4. In a machine gun of the barrel recoiling type, the combination with a piston-like member on the gun barrel, of a cylinder in which said member moves during the recoil and forward movements of the barrel, said cylinder being provided with an opening in 115 line with the bore of the barrel and with one or more lateral ports situated in a position behind that normally occupied by the piston-like member when the gun is ready for firing, of a reciprocating lock, a main fusee 120 spring, a fusee upon which said spring operates and means for increasing the leverage of said spring at or near the termination of the rearward movement of the lock.

5. In a machine gun of the barrel recoiling type, the combination with a piston-like member on the gun barrel, of a cylinder in which said member moves during the recoil and forward movements of the barrel, said cylinder being provided with an opening in 130

line with the bore of the barrel and with one or more lateral ports situated in a position behind that normally occupied by the piston-like member when the gun is ready 10 for firing, of a reciprocating lock, a main fusee spring, a fusee upon which said spring operates, links interposed between said spring and said fusee, and a block on said fusee which block at or near the termination of the rearward movement of the lock comes against the rear one of said links to cause it to take a path further away from the axis of movement of the fusee than is customary.

In testimony whereof, I affix my signature
GEORGE HAZELTON.
